UNITED STATES PATENT OFFICE.

WILLIAM H. CLOUD, OF DETROIT, MICHIGAN.

VICE.

SPECIFICATION forming part of Letters Patent No. 295,354, dated March 18, 1884.

Application filed January 23, 1884. (No model.)

To all whom it may concern:

Be it known that I, WILLIAM H. CLOUD, of Detroit, county of Wayne, State of Michigan, have invented a new and useful Improvement 5 in Vises; and I declare the following to be a full, clear, and exact description of the same, such as will enable others skilled in the art to which it pertains to make and use it, reference being had to the accompanying drawings, which 10 form a part of this specification.

My invention consists of the combinations of devices and appliances hereinafter specified, and more particularly pointed out in the claims.

In the drawings, Figure 1 is a side elevation of a device embodying my invention. Fig. 15 3 is a front elevation. Fig. 2 is a rear elevation. Fig. 4 is a separate view of one of the parts. Fig. 5 is a vertical section, showing parts in elevation.

20 The object of my invention is to provide an improved bench-vise adapted for general uses.

More particularly, it consists in an improved vise in which the jaws may be quickly adjusted to and fro to engage with the work, without 25 the necessity of accomplishing this adjustment solely by a screw in the more ordinary way, and in the operation of which the jaws will be perfectly perpendicular to each other in their bearing upon the work.

30 I accomplish my purpose as follows:

As illustrated in the drawings, A and A' are the jaws.

B is a bar provided with a toothed or ratcheted edge, b, said bar provided with an arm, 35 B', at right angles to the toothed section, and with a screw-cut extremity, B². The toothed section of this bar passes freely through the jaw A, said jaw being constructed with a corresponding orifice for this purpose. The jaw 40 A' is divided at its base to admit the arm B', which at its lower extremity is pivoted in its place, as shown at a. Said jaw is also provided with an orifice corresponding to the screw-cut extremity B² of the bar, and allowing a limited play of the jaw thereon by means 45 of its pivotal connection with the extremity of the arm B'. To control the amount of this play, I prefer to construct the bar with a groove of suitable depth and width, a', and to provide 50 the jaw with a stop, a², operating in said groove.

C is any suitable cap-screw tapped and adapted to work upon the screw-cut end of the bar. C' is the operating-handle.

D is any suitable spring adapted to throw the upper end of the jaw back when the pressure of the cap thereon is released. I prefer to construct the jaw A' with suitable spurs, a³, to limit the friction of the end of the cap upon the jaw.

E is a latch suitably pivoted at one end, 60 adapted to engage with the teeth of the bar B. E' is any suitable spring adapted to throw said latch into engagement with said teeth. e is a guide-pin.

The jaw A may be secured upon the bench 65 F in any suitable manner.

The operation of the device is as follows: By depressing the latch it is disengaged from the teeth of the bar B, when the jaw A', with the bar B pivotally connected therewith, may 70 be readily adjusted to and fro in the jaw A, as may be desired, when, by means of the operating-handle, the cap C may be forced forward upon the upper end of the jaw, forcing it forward into a perpendicular and firmly upon 75 the work, the latch being forced upward by the spring to engage with the toothed bar. In releasing the jaw A' from the work, it would be better, obviously, to retract the cap, allowing the jaw to play backward upon its pivoted connection with the arm B', which will result 80 from the action of the spring D, the upper end of said jaw being limited in its play by a stop, a², as before described. By depressing the latch the jaw may be retracted still farther, if desired.

In the construction of the toothed bar, I prefer to manufacture the same with shoulders b' and b², so that the latch will have contact therewith at each side of the toothed portion, affording greater firmness.

What I claim is—

1. In a bench-vise, the toothed bar B, provided with an angular arm, B', and screw-cut extremity B², substantially as described.

2. In a bench-vise, the combination, with one of the jaws, of an angular toothed bar pivoted thereto, said bar constructed with a screw-cut extremity extending through said jaw, and mechanism operating upon said screw-cut ex-

95

100

tremity to operate the jaw, substantially as described.

3. In a vise, the combination, with one of the jaws, of an angular toothed bar pivoted thereto; and having a screw-cut end passing freely through said jaw, and means for reciprocating the upper end of said jaw upon said bar, substantially as described.

4. In a vise, the combination, with one of the jaws, of an angular toothed bar pivoted thereto, said bar constructed with a screw-tapped extremity passing freely through said jaw, a spring to retract the upper portion of said jaw, and means operating upon the screw-cut extremity of the bar to force said jaw into engagement with the work, substantially as described.

5. In a vise, an angular-toothed bar pivoted in one of the jaws, and provided with a screw-cut extremity passing freely through said jaw, and means for reciprocating said jaw upon said bar and for limiting the reciprocation of the same, substantially as described.

6. The combination, in a vise, with the two jaws, of the angular toothed bar, said bar piv-

totally connected with one of the jaws and passing through the other, means for reciprocating one of the jaws upon said bar, and a latch adapted to be thrown into and out of operation with the toothed bar, substantially as described.

7. The combination, in a vise, with a slotted jaw adapted to be secured to a bench, of an angular toothed bar passed freely through said jaw and pivotally connected with the other jaw, said bar constructed with a screw-cut end passed freely through the latter jaw, the construction being such that the upper portion of the jaw may be reciprocated upon the bar, mechanism for giving said jaw a limited reciprocation, and a latch adapted to be thrown into and out of action with said bar, substantially as described.

In testimony thereof I sign this specification in the presence of two witnesses.

WILLIAM H. CLOUD.
